UNITED STATES PATENT OFFICE.

LUDOVIC MARCQ, OF CAMDEN, NEW JERSEY, ASSIGNOR TO C. HOWARD HUNT PEN COMPANY, OF CAMDEN, NEW JERSEY, A CORPORATION OF NEW JERSEY.

MANUFACTURE OF PENS.

1,356,543.

Specification of Letters Patent. Patented Oct. 26, 1920.

Application filed March 10, 1920. Serial No. 364,692.

To all whom it may concern:

Be it known that I, LUDOVIC MARCQ, a citizen of the Republic of France, residing at Boulogne-sur-Mer, Department of Pas-de-5 Calais, France, temporarily residing in Camden, county of Camden, State of New Jersey, have invented a new and useful Improvement in the Manufacture of Pens, of which the following is a full, clear, and 10 exact description, reference being had to the accompanying drawings, which form a part of this specification.

My invention relates to an improved process for the manufacture of pens, whereby 15 the necessary operations are greatly simplified, reducing the labor requirements, and the cost of production, and which produces a pen of superior quality.

Heretofore in the manufacture of pens, 20 the pen is blanked out of the stock and the blank is subjected to the various operations of slotting, annealing, shaping, hardening and tempering. After the tempering operation, which gives the necessary resiliency or 25 spring, and before splitting the point to form the nibs, the pen is ground on a emery wheel.

The grinding of the pen is highly important, in that it causes the pen to better retain 30 the ink when dipped and aids in causing the nibs to remain in proper relation after they are formed by splitting, and is an essential operation in the production of any high grade pen.

35 In the present method of manufacture, the pens are ground by hand, one by one, or placed by an operative upon a revolving holder, which presents the pens successively to the grinding wheel and drops them into a receiver after they have been ground.

The present methods of grinding are open to a number of serious objections, primarily, the excessive labor requirements necessary to handle each pen separately and because 45 of the loss due to waste, arising, at an advanced stage in the production, from burning and drawing the temper from the pens and from irregularity of grinding.

In accordance with my invention, I submit the stock to a grinding operation as a 50 preliminary step to the operations of blanking, slotting, annealing, shaping, hardening and tempering, etc., whereby I eliminate the disadvantages of the present methods and

produce a superior pen, at a greatly reduced 55 cost.

The stock, usually in the form of a ribbon or band, is preferably ground throughout that portion of its surface which corresponds to that part of the finished pen from 60 the ears to near the point. The grinding may be done with an emery wheel or other form of grinder, or the grinding may be imitated and the ground effect produced, by means of any form of a serrated or corrugated metal wheel, or by any other suitable 65 means, and in referring to "grinding" I mean to include any imitation thereof or effective substitute therefor.

I will now proceed to describe a mechanism 70 capable of carrying out the process embodying my invention, with reference to the accompanying drawing, in which—

Fig. 1 is a plan view of a section of pen stock with a double row of pen blanks outlined.

Fig. 1^A is a plan view of a section of pen stock with a single row of pen blanks outlined.

Fig. 2 is an end elevation of a grinding 80 machine.

Fig. 3 is a sectional side view of the grinding machine.

Fig. 4 is a top view of a finished pen.

Fig. 5 is a diagrammatic view of a device 85 for stamping out the pen blanks from the stock.

Fig. 6 is a diagrammatic view of a device for slotting or piercing a pen blank.

Fig. 7 is a diagrammatic view of a device 90 for shaping or forming a pen.

Fig. 8 is a diagrammatic view of a device for slitting a pen to form the nibs.

The stock *a*, comprising a band or ribbon of suitable metal, of sufficient width to permit a double row of pen blanks *b* to be stamped out, is passed between a grinding wheel *d* and an idle roll *e* and led between a pair of suitably mounted feed rolls *c*, one 95 of which is adapted to be driven, and which serve to draw the stock past the grinding wheel. The grinding wheel *d* is carried by a shaft *f*, journaled in a frame *g* and driven through a pulley *h* connected to any suitable source of power. The grinding wheel 100 is preferably proportioned to grind the stock to a width corresponding substantially to that part of the stock forming the 105

nibs of the pens and the stock is guided so that the wheel will grind it centrally, as indicated at *i*. The exact width of the ground portion is a matter of choice, but it is preferable that the ground portion shall not extend to the extreme point of the pen.

Fig. 1^A shows diagrammatically the application of my invention to a section of stock *a'* from which a single row of pens as *b* are to be stamped. In this case the stock is ground adjacent one of its edges corresponding to that portion of the pen from the ears to near the point, as shown at *i'*.

After the stock is ground, the pen blanks are stamped out by means of a die *n* and a suitably operated punch *o*, between which the stock is drawn by suitably driven feed rolls *p*, *p'*. The blanks, as *b*, are then slotted as at *k* by means of a die *r* and a suitably driven punch *s*. The slotted blanks are then annealed, by heat treating, and formed or shaped by means of a die *t* and a suitably driven punch *u*. The pens are then hardened and tempered after which they are slit to form the nibs by means of shear *v*, the pens being positioned by a stop *w*. The completed pen *j*, having the slot *k* and split as at *m*, is then finished in any customary manner.

Having now fully described my invention, what I claim and desire to protect by Letters Patent is:

1. In the manufacture of pens, the process which comprises grinding the metal stock from which a multiplicity of pens are to be formed and subsequently forming the pens from the ground stock.

2. In the manufacture of pens, the process which comprises grinding the metal rib-

bon constituting the stock from which the pens are to be manufactured so that when the pens are formed therefrom the desired parts of the individual pens will be ground preparatory to forming, from the metal ribbon, the individual pen blanks.

45

3. In the manufacture of pens, the process which comprises grinding the metal stock from which a multiplicity of pens are to be formed and then forming from the ground stock the individual pen blanks and subjecting them to mechanical and metallurgical operations adapted to convert the pen blanks into finished pens while preserving the original grinding.

50

4. In the manufacture of pens, the process which comprises performing the following operations in the following order: grinding the metal stock from which a multiplicity of pens are to be formed, stamping out and slotting the individual pen blanks, annealing, shaping, hardening and tempering, and slitting.

60

5. In the manufacture of pens, the process which comprises grinding the metal ribbon from which the pens are to be formed along a zone extending continuously lengthwise of the ribbon and across that part of the width of the ribbon corresponding approximately to the part of the ribbon from which the nibs of the pens are to be formed, and subsequently performing the operations of stamping out and slotting, shaping, hardening, tempering and slitting.

70

In testimony of which invention, I have hereunto set my hand, at Camden, N. J., on this 6th day of March, 1920.

75

LUDOVIC MARCQ.
